UNITED STATES PATENT OFFICE

2,438,591

EDGE GUARD FOR HAND LUGGAGE

George Henry Wheary, Jr., Racine, Wis., assignor
to Wheary, Incorporated, Racine, Wis., a corporation of Wisconsin

Application June 3, 1946, Serial No. 674,062

2 Claims. (Cl. 190—37)

1

This invention relates to luggage and refers more particularly to hand luggage cases of the type commonly referred to as suitcases.

Suitcases and other hand luggage cases must be of relatively light construction if they are to be conveniently carried by the traveler, and, as is well known, lightweight construction is imperative for travel by air. It is, therefore, customary to construct the better types of suitcases of a relatively thin but stiff panelling covered with leather or an ornamental fabric.

This type of construction is sturdy enough for the ordinary rigors of travel, but hand luggage is subjected to considerable abuse by porters, baggage agents, expressmen and the like. Travelers themselves, moreover, frequently use a suitcase as an improvised seat, subjecting it to possible collapse or deformation.

Much of the abuse to which a suitcase is subjected is borne by the edges of the case with the result that the fabric or leather covering of the case quickly becomes worn and damaged at these areas.

It is, therefore, an object of this invention to provide a lightweight grille or guard which is adapted to be installed along the edges of a suitcase or other article of hand luggage to reinforce and protect the same.

A further object of this invention resides in the provision of a lightweight ornamental guard for application to the edges of a suitcase or other article of hand luggage which may be inexpensively stamped from a single piece of sheet material.

Another object of this invention resides in the provision of an inexpensive bumper guard for the edges of a suitcase or traveling bag which will at once reinforce the same and enhance its attractiveness.

Still another object of this invention resides in the provision of a guard for the purpose described having a plurality of bumpers thereon adapted to occupy positions raised above the surfaces of adjoining sides of a suitcase or other article of hand luggage to which the guard is applied for preventing other surfaces from coming into rubbing contact with the sides of the case and scuffing them.

With the above and other objects in view which will appear as the description proceeds, this invention resides in the novel construction, combination and arrangement of parts substantially as hereinafter described, and more particularly defined by the appended claims, it being understood that such changes in the precise embodiment of the hereindisclosed invention may be made as come within the scope of the claims.

2

The accompanying drawing illustrates one complete example of the physical embodiment of the invention constructed in accordance with the best mode so far devised for the practical application of the principles thereof, and in which:

Figure 1 is a perspective view of the grille of this invention;

Figure 2 is a sectional view of a portion of the grille taken along the line 2—2 of Figure 1;

Figure 3 is a perspective view of the grille of this invention illustrating its application to an edge of a luggage case; and

Figure 4 is a perspective view of a portion of the grille illustrating a slightly modified manner of fastening the same to a luggage case.

Referring now to the accompanying drawing, in which like numerals indicate like parts throughout the several views, the numeral 1 designates generally the guard of this invention.

20 The guard comprises a series of angle shaped bumpers 2, with each of the bumpers constituted by a pair of legs or fingers 3, integrally joined together at an angle having its apex at 4.

This angle is such as to receive an edge portion 25 of a suitcase 5 such as the edge 6 shown in Figure 3. By way of example, in the particular case shown, the edge 6 is formed by the juncture of two adjacent sides of the body section of the case.

The legs have a substantially channel-shaped 30 cross section as shown in Figure 2, and with the guard in its position of use, the open sides of the channels face inwardly toward the sides of the case, and the backs 7 of the channels are outermost, serving as the impact receiving surface of 35 the bumper.

The bumpers are joined together and held in spaced apart bead-like relationship by web portions 8. These web portions 8 lie inwardly of the backs 7 of the channel-shaped bumpers to give 40 the guard the appearance of a grille, and so that only the bumper backs project outwardly to protect the edge of the case over a relatively wide surface. The web portions 8 join the bumpers at the apexes of their angularly connected legs 45 or fingers and also extend around the edge 6 of the case between the bumpers to completely cover the edge of the case.

Pointed tangs 9 formed integrally with each of the legs 3 which project from one side edge of 50 the guard facilitate attachment of the guard in place along the edge of a luggage case. The tangs are preferably formed as extensions of the backs 7 of the channels bent downwardly as shown to close the ends of the channels.

In installing the grille the tangs 9 are driven into the side of the suitcase and it is obvious that

they may be of sufficient length to enable the same to be clinched over on the inside of the case to secure the grille against displacement. Holes 10 are provided in the channel backs 7 of certain of the other legs of the bumpers to receive rivets which pass through the wall of the suitcase and cooperate with the tangs 9 in holding the grille securely in position.

If desired the tangs 9 on the legs 3 may be replaced by rivet receiving holes 10 as shown in Figure 4, so that both legs will be secured by rivets or other similar fastening means. In this way a somewhat more rigid attachment and better reinforcement for the case is achieved. In either case, however, the ends of the channel shaped legs are closed by end walls bent down from the backs of the channels.

Although the grille here shown and described is primarily adapted to be stamped from a single piece of sheet metal, it is obvious that it may be fabricated from a plurality of pieces of material or may be molded from plastics.

Numerous other variations in structure and shape are possible, and it is to be understood that the appended claims are not limited to the specific embodiment here shown and described, but comprehend such modifications thereof as come within their scope.

From the foregoing description taken in connection with the accompanying drawing, it will be readily apparent that this invention provides an inexpensive lightweight guard or grille which will reinforce an edge of a suitcase or other article of hand luggage and protect it against blows and frictional scuffing, and at the same time enhance the appearance of the luggage.

What I claim as my invention:

1. A grille stamped from a single sheet of material and adapted to be secured to the side walls of a suitcase or the like at a juncture thereof defining one edge of the case to reinforce and protect the same, comprising: a strip having alternate web and finger portions shaped to fit around and cover said edge of the case and to lie lengthwise therealong; said finger portions being formed by a plurality of spaced channel shaped fingers, integral with the web portions and projecting beyond the edges of the web portions to extend around said edge of the case and overlie the marginal portions of the sides of the case adjacent to said edge, and with the open sides of

the channels facing inwardly toward the sides of the case and the backs of the channels outermost and raised outwardly above the surface of the web portions; and pointed tangs formed as extensions of the backs of the channels of the fingers which project from one side edge of the web portions bent downwardly and inwardly to close the ends of said channels, said tangs being adapted to be driven into one side of the case at a distance from said edge to be covered by the grille.

2. A grille stamped from a single sheet of material and adapted to be secured to the side walls of a suitcase or the like at a juncture thereof defining one edge of the case to reinforce and protect the same comprising: a strip having alternate web and finger portions shaped to fit around and cover said edge of the case and to lie lengthwise therealong, said finger portions being formed by a plurality of spaced channel shaped fingers integral with the web portions and projecting beyond the edges of the web portions to extend around the edge of said case and overlie the marginal portions of the sides of the case adjacent to said edge, and with the open sides of the channels facing inwardly toward the sides of the case and the backs of the channels outermost and raised outwardly above the surface of the web portions; end closures for the fingers comprising extensions on the backs of the channels of the fingers bent downwardly and inwardly to close the ends of said channels; and means at the ends of the fingers for securing the same to the sides of the case at a distance from the edge thereof to be covered by the grille.
